(57) **CLAIM**

The ornamental design for a headlamp, as shown and described.

DESCRIPTION

FIG. 1 is a front perspective view of a headlamp showing my design.

FIG. 2 is a rear perspective view of the headlamp in FIG. 1.

FIG. 3 is a front elevation view of the headlamp in FIG. 1.

FIG. 4 is a rear elevation view of the headlamp in FIG. 1.

FIG. 5 is a left side elevation view of the headlamp in FIG. 1.

FIG. 6 is a right side elevation view of the headlamp in FIG. 1.

FIG. 7 is a top plan view of the headlamp in FIG. 1.

FIG. 8 is a bottom plan view of the headlamp in FIG. 1; and, FIG. 9 is an enlarged view of a portion of the headlamp labeled 9 in FIG. 1.

The evenly spaced broken lines shown in the drawings depict portions of the headlamp that form no part of the claimed design. The dash-dot broken lines shown in FIGS. 1 and 9 are for the purpose of indicating the enlarged partial views, and form no part of the claimed design.
